Inventor:

J. O. Blythe

UNITED STATES PATENT OFFICE.

JOHN O. BLYTHE, OF GERMANTOWN, PENNSYLVANIA, ASSIGNOR TO HIMSELF AND JOSEPH W. JONES.

VENTILATING HAT AND CAP.

Specification of Letters Patent No. 33,121, dated August 20, 1861.

To all whom it may concern:

Be it known that I, JOHN O. BLYTHE, of Germantown, in the city of Philadelphia and county of Philadelphia and State of Pennsylvania, have invented a new and useful and Improved Ventilating Cap or Hat; and I do hereby declare that the following is a full, clear, and exact description of the construction and operation of the same, reference being had to the annexed drawings, making a part of this specification, in which—

Figure 1 is a perspective view of the side of the cap; Fig. 2 a perspective view of the back part of the cap; Fig. 3 side view of a hat; Figs. 4, 5, and 6, perspective views of attachments or hinges for the cap or hat; Fig. 7, screw and nut.

a—b in Figs. 1, 2, 3 are the two sections 20 into which the cap is divided, *a—a* being the upper section and *b—b* the lower; *c—c* the space or opening between them, the cap sections being set apart by the attachments *d—d*.

d—d in Nos. or Figs. 4, 5, 6 are the arms 25 of the attachments; *E—E*—the shoulder against which the arm impinges or strikes on being thrown back. The cap or hat is made in two sections the upper shutting 30 closely down over the under section and resting on the attachments. The attachments are placed on the inside or outside of the cap as seen in Fig. 1—marked *d—d*—one on each side and one back as seen in Fig. 2—

and in the model they are secured by screw 35 and nut as seen in No. 7. Each of the attachments has a projection or shoulder against which the arm strikes on being reversed and holds the cap sections apart as seen in Fig. 2 of attachment *d—d—E*. The 40 same is also seen in Figs. 4 and 5—*d—E*. By operating these attachments the cap may be opened at the rear and closed in front or open in front and closed back or open on one side and closed on the other or all open 45 all around. The top of the cap may be made broad so as to form a complete shade for the head, and the connection between *a—* and *E* may be made of loose cloth so that the broad top may be thrown forward or back 50 or on either side affording protection from sun; and the cap being thrown open and held by the attachments ventilation is complete the head being protected and kept cool 55 in the hottest sunshine.

The cap or hat may be made of any, and of the lightest materials suitable and the attachment also.

What I claim as my invention and desire to secure by Letters Patent is—

A ventilating or extension cap or hat formed by the combination and arrangement of the parts *a—b—d—* and *—E—* substantially as herein described.

J. O. BLYTHE.
